UNITED STATES PATENT OFFICE.

CHARLES M. FEIST, OF SIOUX CITY, IOWA, ASSIGNOR OF FORTY-NINE ONE-HUNDREDTHS TO EDWIN L. KIRK, OF SIOUX CITY, IOWA.

TROLLEY-STAND.

979,940.

Specification of Letters Patent. Patented Dec. 27, 1910.

Application filed April 13, 1910. Serial No. 555,159.

To all whom it may concern:

Be it known that I, CHARLES M. FEIST, a citizen of the United States, residing at Sioux City, in the county of Woodbury and State of Iowa, have invented new and useful Improvements in Trolley-Stands, of which the following is a specification.

The present invention relates to improvements in trolley stands, and comprehends, generally, the production of a dust-proof and water-tight device of that type capable of self-oiling, this object being attained by the construction of the top member of the device in such a manner as to completely 10 close the bearing portions of the bottom member, said members being further so constructed and arranged with respect to each other that, as a result, inter-communicating oil-wells and passages are produced, thereby 15 maintaining all of the bearing surfaces in a state of constant lubrication.

A structural embodiment of the invention is illustrated in the accompanying drawing, wherein:

25 Figure 1 is a vertical sectional view of the improved trolley stand; and Fig. 2 is a horizontal sectional view thereof taken on the line 2--2 of Fig. 1.

As shown in said drawing, the stand is 30 composed of two essential elements, namely, a top member or cap, designated in a general manner by the letter A, and a bottom member or base similarly designated by the letter B, the former member carrying the pole 35 socket C and compression spring D which may be of any conventional or preferred type. The base B comprises a dished plate 3 provided with a centrally-located bearing post 4 and an upstanding annular wall or 40 flange 5 arranged concentrically of and in spaced relation to post 4. In the construction illustrated, the flange 5 is formed integral with plate 3, and the bearing post is constituted by a pin riveted at its lower end 45 to said plate, as shown in Fig. 1. Cap A is likewise preferably of integral construction, and is rotatably mounted upon base B. It is formed with spaced inner and outer annular walls 6 and 7 concentrically arranged 50 and depending vertically from the crown portion 8, the latter having an axial aperture through which passes the connecting bolt 9. The threaded lower portion of this bolt seats

in an opening in post 4, and its enlarged head in a recess in the cap crown.

55 In assembling the parts, the cap is fitted upon the base in such a manner that the post is received within the inner wall 6, and the flange 5 within the space between the latter and the outer wall 7, a washer 10 being interposed between the upper end of said post and the under face of the crown 8. (See Fig. 1.) By reason of this arrangement, it will be seen that the cap is supported entirely upon the bearing post, and is capable 60 of a free rotary movement thereon, the upper edge of said flange terminating short of the top wall of the annular space between the walls 6 and 7, while the lower edges of 65 said walls in turn terminate short of the bottom wall of the dished base. As a result, friction between the moving parts is obviated at the points specified. To further this result, and to provide for continuous lubrication of said parts, the same are so proportioned with respect to reach other that 70 an annular chamber 11 is produced between the inner surface of wall 6 and the peripheral surface of the post, and similar chambers 12 and 13 between the inner and outer 75 surfaces of flange 5 and the adjacent surfaces of the walls 6 and 7, the latter chambers communicating with each other at their upper ends by way of the conduit 14, (produced by the above-mentioned arrangement 80 of flange 5), while the chambers 12 and 11 have communication with each other at their lower ends through the similarly produced conduit 15. Additional communication between the chambers 12 and 11 is afforded by 85 a series of horizontal ports 16 formed through wall 6. The chamber 12 thus constitutes an oil well, and may be filled through a port 17 formed in the crown 8, this port being normally closed by a cover 90 plate 18 mounted on the outer face of said crown and connected thereto by a screw or similar device 19 which is set into the head of bolt 9. Cover 18 is formed with a port 100 20 which is brought into registration with the port 17 when it becomes necessary to fill the well. The chamber 11 is designed to receive a series of anti-friction bearings 21, herein shown as in the form of vertically arranged rollers which are co-extensive in 105 length with the effective or working por-

tion of post 4, the rounded lower ends of said rollers resting upon the dished portion of the base.

The height of the oil well is such that it 5 extends an appreciable distance above the post top and the washer 10, as shown in Fig. 1, and since said well communicates with the chamber 11 through the conduit 15 and ports 16, the rollers, the post and the 10 inner surface of the adjacent wall 6 will be maintained in a state of continuous lubrication at all times. The production of said conduit will, moreover, enable any grit contained in the oil to settle thereinto, and since 15 the well is likewise in communication through the upper conduit 14 with the outer chamber 13, any grit contained in the oil which may flow into the latter will settle in the dished base, thus avoiding the wear 20 which would otherwise take place. It will be seen, therefore, that the entire stand is rendered dust-proof and water-tight by the construction above described, and that the moving parts are completely protected in 25 consequence, and maintained in a state of perfect lubrication, while the mounting of the cap is such as to insure free rotary movement thereof without occasioning the production of friction between it and the body.

30 I claim as my invention:

1. A trolley stand comprising, in combination, a dished base adapted to contain a lubricant and provided with a central bearing post; a cap rotatably mounted upon said 35 post and formed with a depending annular wall inclosing the same and spaced therefrom; said wall terminating at its lower edge short of said base to admit the lubricant into the space between said wall and post; and a 40 series of elongated anti-friction rollers arranged in the said space and resting at their lower ends upon said base.

2. A trolley stand comprising, in combination, a base provided with a bearing post 45 and with an annular flange surrounding the same and spaced therefrom; a cap rotatably mounted upon said post and formed with outer and inner depending annular walls arranged in spaced relation to each other, the inner wall being received in the space 50 between said post and flange, and the outer wall inclosing the latter; and a pole socket carried by said cap.

3. A trolley stand comprising a base member; a rotatable cap; and means on said base for supporting said cap, said base and cap having parts coöperating to produce an inclosed annular oil well.

4. A trolley stand comprising a dished 60 base provided with a bearing post and with an annular flange encircling the same and spaced therefrom; and a cap rotatably mounted upon said post and formed with a depending annular wall received in the space 65 between said post and flange and having its

opposite faces spaced from the adjacent faces of said post and flange to produce a pair of lubricant chambers, said wall terminating short of said base to afford a means of communication between said chambers.

5. A trolley stand comprising a dished base provided with a bearing post and with an annular flange encircling the same and spaced therefrom; and a cap rotatably mounted upon said post and formed with a 70 depending annular wall received in the space between said post and flange and having its opposite faces spaced from the adjacent faces of said post and flange to produce a pair of lubricant chambers, said wall having 75 a series of ports formed therethrough and terminating at its lower end short of said base.

6. A trolley stand comprising a dished base provided with a bearing post and with an annular flange encircling the same and spaced therefrom; a cap rotatably mounted upon said post and formed with a depending annular wall received in the space between said post and flange and having its 80 opposite faces spaced from the adjacent faces of said post and flange to produce a pair of chambers, one of which constitutes an oil well, said wall terminating short of said base to afford a means of communication 85 between said chambers; and a series of anti-friction rollers arranged in the other chamber and resting at their lower ends upon said base.

7. A trolley stand comprising a base provided with a bearing post and with an annular flange encircling the same and spaced therefrom; a cap rotatably mounted upon said post and formed with a depending annular wall encircling said post and interposed between the latter and said flange, said 100 wall being spaced from said post and flange to produce a pair of annular chambers, and being ported to provide communication therebetween; and a series of anti-friction 105 rollers arranged in one of said chambers, the other chamber constituting an oil well.

8. A trolley stand comprising a base provided with a bearing post and with an annular flange encircling the same and spaced therefrom; a cap rotatably mounted upon said post and formed with inner and outer depending annular walls arranged in spaced relation to each other, the inner wall being received in the space between said post and flange, and the outer wall encircling the latter, said inner wall being spaced from said 115 post and flange to produce a pair of annular chambers in communication with each other; and a series of anti-friction rollers arranged 120 in one of said chambers, the other chamber constituting an oil well.

9. A trolley stand comprising a base member; a rotatable cap; means on said base for supporting said cap, said base and 125

cap having parts coöperating to produce an inclosed annular oil well, and said cap having an inlet port leading to said well; and a cover rotatably mounted upon said cap and having a port arranged to be brought into and out of registration with the first-named port when said cover is rotated.

10. A trolley stand comprising a dished base provided with a bearing post, and with an annular flange encircling the same and spaced therefrom; a cap rotatably mounted upon said post and formed with a depending annular wall received in the space between said post and flange and having its opposite faces spaced from the adjacent faces of said post and flange to produce a pair of lubricant chambers, said wall terminating short of said base to afford a means of communication between said chambers, and said cap having an inlet port leading to one of said chambers; and a cover rotatably mounted upon said cap and having a port arranged to be brought into and out of registration with the first-named port when said cover is rotated.

11. A trolley stand comprising a dished

base provided with a bearing post, and with an annular flange encircling the same and spaced therefrom; a cap rotatably mounted upon said post and formed with a depending annular wall received in the space between said post and flange and having its opposite faces spaced from the adjacent faces of said post and flange to produce a pair of lubricant chambers, said wall being ported to provide communication between said chambers, and said cap having an inlet port leading to one of said chambers; a series of anti-friction rollers arranged in the other chamber; and a cover rotatably mounted upon said cap and having a port arranged to be brought into and out of registration with the first-named port when said cover is rotated.

In testimony whereof I have hereunto set my hand in presence of two subscribing witnesses.
